BEET TOPPER

Heinz Carl Oppel, Boise, Idaho

Application September 7, 1954, Serial No. 454,297

5 Claims. (Cl. 56—121.4)

My invention relates to improvements in beet toppers. In the harvesting of sugar beets the top foliage has to be removed and the crown portion of the beet has to be removed also. The foliage and crown portion are often removed by two devices, one of which is a beater that whips the foliage from the crown of the beet and the other device is a scalper which cuts the crown from the beet which has already had the foliage removed. In removing the crown from a beet it is essential to have a locating device in advance of the cutting tool that cuts the crown from the beet so as to make sure that the top of the beet is removed at the desired level. Otherwise, there would be too much waste on the beets that stand high out of the ground and insufficient removal of those that are lower. It is known therefore to provide a feeler or indexing roller in connection with a knife to cut off the crown of the beet. However, devices using the feeler and the knife have not proven satisfactory to date in the manner of eliminating the clogging of the knife with foliage, sticks and the like. Another difficulty in the use of the roller and knife combination has been the danger of breaking the knife and putting the machine out of operation.

It is the principal purpose of my invention to provide in a beet topper which employs a locating or indexing roller in combination with a knife, means whereby the roller and the knife cooperate to prevent any clogging of the knife by foliage, sticks and the like, and to prevent breakage of the knife in the event that it is engaged by a stone or the like.

More particularly it is a purpose of my invention to provide in a beet topper the combination of an indexing roller which travels faster than ground speed and which is provided with a spiral rib on its periphery to wipe the foliage in a direction axially of the roller, together with a crown slicing knife which is pivotally mounted to swing beneath the roller about an axis that is at the side of the roller from which the roller wipes the foliage so that the action of the roller tends to clean the knife.

It is also the purpose of my invention to provide in a beet topper having the characteristics just described, a spring means which yieldingly opposes movement of the knife rearwardly with respect to the roller.

Other objects and advantages of the invention will appear more fully from the following description and the accompanying drawings which illustrate a preferred form of the invention. It should be understood, however, that the drawings and description are illustrative only and are not intended to limit the invention except insofar as it is limited by the claims.

In the drawings:

Figure 1 is a fragmentary plan view of a beet harvesting machine embodying my improved beet topper;

Figure 2 is a sectional view taken on the line 2—2 of Figure 1;

Figure 3 is a sectional view taken on the line 3—3 of Figure 1;

2

Figure 4 is a bottom plan view looking up at the indexing roller and the knife; and

Figure 5 is a sectional view taken substantially on the line 5—5 of Figure 3.

5 Referring now in detail to the drawings and particularly to Figures 1, 2 and 3, my invention is shown as an attachment to a beet harvester frame 10. The beet topper comprises a drive wheel 11 which has a shaft 12 mounted in bearings 13 and 14. The bearings 13 and 14 are carried by brackets 15 and 16 that extend rearwardly from a cross beam 17. The cross beam 17 is supported at one end by the wheel 11 and at the other end by the frame 10. My beet topper is drawn by the shaft 12 and the beam 17 and the shaft 12 also supplies the power to rotate the indexing roller 18.

15 The roller 18 is secured on a shaft 19 which is journaled in bearings 20. The bearings 20 are mounted on an inverted U-shaped frame 21. Two bars 22 and 23 are pivotally secured to the frame 21 and extend forwardly to the shaft 12 where they are secured to bearing members 24 and 25 that are rotatably mounted on the shaft 12. Collars 26 properly position the bearing members 24 and 25 lengthwise of the shaft 12. The bars 22 and 23 are connected by a cross brace 27 and form with the brace 27 a rigid link pivotally connecting the trailing frame 21 to the main supporting frame composed of the parts 12 to 17 inclusive.

20 In addition to the connection just described, the inverted U-shaped frame 21 is also connected to the beam 17. A mounting bracket 28 is provided on the top of the frame 21 and a similar mounting bracket 29 is provided on the beam 17. A connecting link 30 extends between the brackets 28 and 29 and is secured to the brackets by bolts 31. It will be noted that the bracket 29 has several apertures 32 therein so as to provide for 25 considerable adjustment of the front end of the link 30 inward to vary the position of the frame 21 with respect to the vertical. By moving the bolt 31 at the front end of the link 30 downward, the top of the frame 21 will be moved forward with respect to the lower end. The frame 21 in so moving, pivots about its connections at 33 and 34 to the bars 22 and 23.

30 The shaft 12 has a sprocket wheel 35 thereon and the shaft 19 has a sprocket wheel 36 thereon. A chain 37 connects the sprocket wheels 35 and 36 so as to drive the roller 18 in response to rotation of the wheel 11. The sprocket wheels 35 and 36 are chosen of such size that the roller 18 is turned at a greater speed than the speed of the wheel 11 along the ground so that the roller 18 35 wipes across the beet tops in a rearward direction as the machine moves forwardly.

The frame 21 in addition to mounting the roller 18, also

45 mounts a knife 38 which cuts the crowns from the beets. A tubular bearing member 39 is secured by ears 40 and bolts 41 to the side of the frame 21 that is nearest the chain 37. A shaft 42 is journaled in the bearing tube 39 and carries a knife mounting plate 43 at its lower end. The plate 43 extends forwardly and outwardly from the shaft 42 and has the knife 38 fastened to it by bolts 44.

50 The normal position of the knife 38 with respect to the roller 18 is directly beneath the roller with its cutting edge extending from the point substantially beneath the sprocket wheel 36 across and rearwardly beyond the bearing 20 at the other side of the frame 21.

55 The shaft 42 is supported against downward movement in the tube 39 by a collar 45 that is secured to the shaft 42. The tube 39 and the collar 45 form bearings on the frame 21 rotatably supporting the shaft 42. The shaft 42 also has a lever arm 46 secured to the top end thereof. This arm extends across the top of the frame 21 to a resilient stop member 47 that is mounted on the frame 21. The stop member 47 limits the forward swing-

ing movement of the knife 38. A spring 48 is secured to the lever arm 46 and extends forwardly to the link 30 to which it is also secured. The function of the spring 48 is to yieldingly maintain the knife 38 in its correct position beneath the roller 18 to slice across the beet tops and to return the knife 38 after the slicing operation, to the same position. The tension on the spring 48 may need to be adjusted to fit the particular operation. In order to accomplish the adjustment the lever arm 46 is provided with a multiplicity of apertures 49 and the link 30 has a plurality of opertures 50 therein.

In normal operation the weight of the roller 18 and the frame 19 causes the roller to follow the beet top projections so that it rolls over each beet top and when one top is high and the next one lower, the roller provides the indexing or rise and fall necessary to position the knife 38 at the right height for each beet. When the machine is being transported, the frame 21 can be lifted to bring the roller 18 and the knife 38 above the ground. A chain 51 secured to a hasp 52 on the frame 21, hooks over a cross bar 53 on the frame 10 to hold the frame 21 elevated.

The roller 18 is provided with means to shift material that is going over the knife in a direction away from the pivoted leading end of the knife 38 and toward the free trailing end of the knife. This means, as shown, is a round rib 54 which is fixed on the periphery of the roller 18 and which follows a spiral path around the roller 18. It is obvious, of course that some other deflecting means might be used for this same purpose. It will be remembered that the roller 18 travels faster at its surface than the ground speed of the machine. Because of this higher speed of rotation, the ribs 54 serve to move the foliage and any trash that may tend to hang to the knife toward the free end of the knife for discharge.

Another very important factor in maintaining the knife clean is the combining of the roller with its ribs and a knife which yields rearwardly in cutting so as to perform a slicing operation and then snap back into position as soon as the cutting of a beet top is completed. The snap back action of the knife tends to throw any beet crown or other material caught on the knife outwardly free of the knife when the knife is stopped suddenly by engagement of the arm 46 with the stop 47. In effect the knife is being repeatedly shaken or tapped in such a way as to prevent accumulation of trash thereon and the spiral rib 54 on the roller 18 is continuously operative to shift the loosened trash toward the free end of the knife.

It is believed that the nature and advantages of my invention will be clear from the foregoing description.

Having thus described my invention, I claim:

1. A beet topping device comprising a main supporting frame, a drive wheel, a trailing frame pivotally mounted to said main frame, an indexing roller rotatably mounted in the trailing frame, driving means connecting the drive wheel to the indexing roller whereby to drive the roller in the same direction as the drive wheel at a speed substantially greater than the speed of the drive wheel, a horizontally disposed knife positioned beneath the roller, means at one end of the knife mounting the knife to the trailing frame for limited swinging movement rearwardly of the roller, an upstanding rib fixed to the periphery of the indexing roller, said rib following a spiral path around the roller whereby to shift material clinging to the knife to the free end thereof, and spring means connecting the knife and the trailing frame to oppose the rearward movement of the knife.

2. A beet topping device comprising a main supporting frame, wheels supporting said frame, a trailing frame pivotally mounted to said supporting frame, an indexing roller rotatably mounted in the trailing frame, drive

means connected to said roller whereby to rotate the roller in the same direction as the supporting wheels at a surface speed substantially greater than the speed of the wheels, a horizontally disposed knife positioned beneath the roller, means on the trailing frame mounting the knife for swinging movement rearwardly in a horizontal direction and a spring connecting the knife and trailing frame opposing rearward swinging movement of the knife, and an upstanding rib fixed to the periphery of the indexing roller, said rib following a spiral path around the roller whereby to shift material clinging to the knife to the end thereof.

3. In a beet topping vehicle having a wheel supported main frame, an upright trailing frame, upper and lower links pivotally connecting the trailing frame to the main frame, an indexing roller journaled in said trailing frame and having a smooth rib on its periphery extending spirally around the roller operable to urge material engaging the roller axially of the roller by rotation of the roller, a knife supporting shaft pivoted on the trailing frame at one end of the roller, means to rotate the roller in a direction to cause the rib thereon to move the engaged material away from said end of the roller, a knife mounting plate extending forwardly from the shaft, a knife fixed to said plate and extending beneath the roller to the other end thereof, a lever arm on the shaft, a spring connecting the lever arm to said upper link and urging the knife forward, and a resilient stop member on the trailing frame limiting the forward movement of the knife.

4. In a beet topping vehicle having a main frame and a trailing frame pivoted to the main frame, an indexing roller journaled in the trailing frame and adapted to ride over beets to be topped, a knife supporting shaft pivoted on the trailing frame at one end of the roller, and rearwardly of the roller axis, a knife mounting plate fixed to the shaft and extending forwardly, a knife secured to the plate and extending beneath the roller whereby turning of the shaft swings the knife in a slicing movement axially of the roller in part and in part in the direction of movement of the vehicle, spring means connected to the shaft and the trailing frame urging the knife forwardly in the direction of movement of the vehicle, and stop means limiting the movement of the shaft by the spring.

5. In a beet topping device, a main supporting frame having supporting wheels, an indexing roller, means rotatably mounting said indexing roller for vertical movement with respect to the main frame, drive means for the indexing roller operable to rotate the roller at a speed greater than the rate of speed of the main frame with respect to the ground, a horizontally disposed knife positioned beneath the roller, means at one end of the knife mounting the knife to the roller supporting means for limited swinging movement in a horizontal plane, an upstanding rib fixed to the periphery of the indexing roller and following a spiral path around the roller whereby to shift material clinging to the knife to the free end thereof, and spring means connected to the knife and opposing the rearward swinging movement.
